UNITED STATES PATENT OFFICE

LAURITZ W. ANDERSEN, OF WATERBURY, CONNECTICUT

TWIN SOCKET LAMP FIXTURE

Application filed May 29, 1930. Serial No. 456,961.

This invention relates to electric lamp fixtures, and more particularly to a shade support having a pair of depending clamping bands for resiliently embracing the opposed 5 sockets of a twin-lamp fixture to permit the shade to be readily rotated around the longitudinal axis of said fixture whenever desired.

One object of this invention is to provide 10 a shade support of the above nature which will be simple in construction, inexpensive to manufacture, easy to install and manipulate, compact, ornamental in appearance, and very efficient and durable in use.

With these and other objects in view there 15 has been illustrated on the accompanying drawings one form in which the invention may be conveniently embodied in practice.

In the drawings:

20 Fig. 1 represents a rear vertical sectional view of the shade, shade holder, and a twin-lamp fixture upon which the shade holder is mounted.

Fig. 2 is a side sectional view of the same 25 on a reduced scale, the section being taken along the line 2—2 of Fig. 1, looking in the direction of the arrows.

This application covers an improvement on 30 the invention disclosed in my copending application for electric lamp shades, Serial No. 343,907, filed March 2, 1929.

Referring now to the drawings in which like reference numerals denote corresponding parts throughout the several views, the numeral 35 10 indicates a hollow supporting base having a two-wire electric conductor cord 11 extending through one side thereof for supplying current to a pair of lamps 12 and 13 located within a pair of threaded sockets 14 and 15, said sockets extending longitudinally 40 in opposite directions from the body portion 16 of a twin-lamp fixture. The body portion 16 has a horizontal tube 17 extending laterally therefrom and said tube 17 is joined by a flexible swivel connection 18 to a vertical supporting tube 19 mounted on said base 10.

The cord 11 passes through the base 10, the vertical tube 19, and the horizontal tube 17, 45 into the body portion 16 of the twin-lamp fixture, where it is connected by the usual

binding posts, not shown, to the center and shell terminals of the sockets 14 and 15. The body portion 16 is provided in its lower section with the usual switch-operating pull-chain 20.

The shade support comprises a pair of resilient circular bands 21 and 22 shaped to fit about the sockets 14 and 15 respectively. Each of the bands 21 and 22 is provided with a pair of upwardly extending straight sections 23 and 24 having inwardly extending apertured ends 25 and 26, said apertures being adapted to be held in overlapping relation by a pair of headed screw bolts 27 and 28, respectively.

In order to connect the clamping bands 21 and 22 to an ornamental shade 35, provision is made of an elongated rectangular holding strip 29 having a depressed central section 30 and a pair of similar depressed apertured end sections 31 and 32. The apertures of the outer depressed sections 31 and 32 are shaped to fit over the depending ends of the bolts 27 and 28, mentioned above. The central depressed section 30 is provided with an upwardly extending threaded stud 33 adapted to pass loosely through an aperture 34 in the lamp shade 35, said stud being adapted to receive an ornamental nut 36 for holding said shade rigidly in position.

As will be clear from Fig. 1, the ends of the holding strip 29 beyond the depressed sections 31 and 32 are bent upwardly at 37 and 38 into alignment with the strip 29 for forming a rigid support for the under surface of the shade 35. The heads 39 and 40 of the bolts 27 and 28 are adapted to be located within a pair of raised sockets 41 and 42 formed in the top of the shade 35 adjacent the central stud 33. The shade 35 has a rear depending wall 43 provided with a vertical slot 44 adapted to embrace the lateral tube 17 to permit the shade to be rotated about the longitudinal axis of the twin-socket fixture.

Operation

In the operation of assembling the device, the bands 21 and 22 will first be slipped over the empty sockets 14 and 15 of the lamp fixture, and the oppositely disposed ends 25

and 26 of said bands are brought into contact with each other. The holding strip 29 will next be placed in the position shown with the depressed end sections 31 and 32 directly under the ends 25 and 26 of said bands, after which the bolts 27 and 28 will be inserted downwardly through the apertures in said ends 25, 26, 31 and 32.

The heads 39 and 40 of said bolts will next be positioned within the sockets 41 and 42 of the shade 35 with the stud 33 extending up through the aperture 34 of said shade. The ornamental nut 36 will then be screwed down upon the stud 33, thus completing the assembly of the device.

One advantage of the present invention is that all portions of the shade-attaching means, except the ornamental nut 36, are concealed within the shade 35.

While there has been disclosed in this specification one form in which the invention may be embodied, it is to be understood that this form is shown for the purpose of illustration only, and that the invention is not to be limited to the specific disclosure but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an electric lamp fixture, a shade, a shade holder having a pair of spaced continuous clamping bands for rotatably clamping around the opposed sockets of a twin socket, the upper parts of said bands engaging the under surface of said shade, and means for detachably locking said shade to said shade holder, said clamping bands completely encircling said sockets.

2. In an electric lamp fixture, a shade, a shade holder having a pair of spaced resilient clamping bands for rotatably clamping completely around the opposed sockets of a twin socket, and means for detachably locking said shade to said shade holder, said clamping bands completely encircling said sockets.

3. In an electric lamp fixture, a shade, a shade holder having a pair of spaced closed clamping bands for rotatably clamping around the opposed sockets of a twin socket, and means for detachably locking said shade to said shade holder, said clamping bands completely encircling said socket.

4. In an electric lamp fixture, a shade, a shade holder comprising a pair of spaced closed bands for rotatably clamping completely around the opposite ends of a twin socket, and an elongated strip for detachably securing said bands to said shade, said clamping bands completely encircling said socket.

5. In an electric lamp fixture, a shade, a shade holder having two resilient bands for

rotatably clamping upon the opposite ends of a twin socket, an elongated strip underlying the upper part of said bands, a threaded stud extending upwardly from said strip through said shade, and a nut outside of said shade for rigidly securing said strip against said shade.

6. In an electric lamp fixture, a shade, a shade holder having a pair of resilient bands for rotatably clamping upon the opposite ends of a twin socket, each of said bands having overlapping ends provided with apertures, and headed alining bolts passing through said apertures, said shade having upwardly extending sockets to receive the heads of said bolts, and means for rigidly attaching said bands against said shade.

7. In an electric lamp fixture, a shade, a shade holder comprising a pair of closed bands for rotatably clamping about the opposite ends of a twin socket, an elongated strip having depressed ends to embrace said bands, a threaded stud extending upwardly from the center of said strip, and a nut screwed upon said stud for holding said shade in position.

8. In a lamp shade holder adapted to be detachably and rotatably attached to a twin socket, a pair of bands for encircling the opposite ends of said sockets, said bands having flat top sections for engaging the underside of said shade, an elongated strip underlying said flat top sections, and means for attaching said strip to said shade.

In testimony whereof, I have affixed my signature to this specification.

LAURITZ W. ANDERSEN.
